Claims priority, application Netherlands February 23, 1948

5 Claims. (Cl. 192—142)

This invention relates to a shaft-positioning device, and more particularly to a shaft-positioning device which includes a pawl knob.

A pawl knob is a system of associated locking discs and pawls which permits of locking a rotary shaft in each of a number of definite positions, for example, the shaft serving to control the capacity of a condenser in a transmitter or a receiver for wireless intelligence or to adjust other tuning members. With the use of pawl knobs control-members may be readily moved from one position to another. Furthermore, apparatus comprising pawl knobs are adapted to be operated by remote control.

For each position of the shaft required to be selected the pawl knob comprises a locking disc and an associated pawl. A movable selecting member, which is referred to as a pawl selector, permits any selected pawl to be caused to co-operate with the locking disc with which it is associated.

A number of such pawl knobs, each of which operates on a separate shaft may be assembled to form a mechanism in which the shafts are adapted to be operated by a common driving arrangement either by hand or with the use of a motor.

A device is known in which the pawl selector of a pawl knob is displaced by the same operating device which causes the pawl knob shaft to rotate, the change of position being carried out in two moving steps of a driving shaft. The first step results in the pawl selector being displaced, the latter being propelled by a link member which derives its movement from the driving shaft. When the pawl selector reaches the selected position, the driving shaft stops, whereupon the second moving step starts, the driving shaft continues to rotate in a sense opposite to that of the first step and a separating device providing for the link member, and hence also the pawl selector remain stationary. On the other hand the pawl knob shaft is rotated during the second step until it is locked by the operative pawl upon reaching the selected position.

Initially, the present device was constructed so that the direction of rotation of the driving shaft had to be reversed with the use of a control-knob. The attention of the operator was required to perform this operation at the correct time.

In an alternative embodiment the direction of rotation is reversed automatically. For this purpose, the device comprises a so-called position switch, which comprises a movable contact arm and a number of stationary contact members. Each stationary contact member is associated with a definite pawl. The contact arm of this position switch is moved simultaneously with the pawl selector, so that each position of the contact arm corresponds with the position of the pawl selector.

During its movement the contact arm contacts successively with each of the stationary contact members. Upon reaching the stationary contact member which is associated with the selected pawl, a circuit is closed and the current brings about reversal of the direction of rotation. This current may, for example, serve as the control-current of a relay, the switch of which reverses the field current of a motor which actuates the driving shaft.

This device has also a limitation. As soon as the contact arm has contacted the selected contact member, it stops moving. If the contact arm moves excessively slowly, the contact surface between the contact arm and the stationary contact member will be small so that the

2

contact is unreliable. It will readily be interrupted due to vibration or to impurities (burning). This phenomenon occurs particularly if the movement of the driving shaft is transmitted to the pawl selector with great retardation, as is generally the case of electric driving. If, on the contrary, the pawl selector and the contact arm move with excessive speed, the contact arm may pass over the selected contact member before the closing current has any effect. Consequently, this device requires a quite defined ratio between transmission of the movements from the driving shaft to the pawl selector and the contact arm.

The invention relates to a device comprising one or more pawl knobs and a common driving arrangement for the pawl selector and the shaft of the pawl knob, in which the disadvantages of the aforesaid known devices are not inherent.

According to the invention, the separating device of the pawl selector and the pawl selector itself have arranged between them a locking element. This locking element is capable of mechanically locking the pawl selector in a number of positions equal to the number of pawls of the pawl knob. In each of these locking positions a pawl is caused to co-operate with the pawl disc with which it is associated.

The locking element may be formed by a pawl wheel and a pawl co-operating therewith and in distinction from the pawls co-operating with the locking discs, this pawl will be referred to as a selector pawl. The pawl wheel follows the rotation of the pawl selector. For each locking position it has one tooth.

The selector pawl may occupy an inoperative position, in which it is clear of the pawl wheel, and an operative position, in which it meshes with the teeth of the pawl wheel.

In this device, the position in which the pawl selector is locked is no longer a function of the instant at which takes place the change of current which results in the change in position of the pawl. After this instant the pawl selector together with the movable contact arm of the position switch and the pawl wheel move on and the selector pawl passes over the back of one of the teeth of the pawl wheel until it engages the next following tooth of the pawl wheel.

Assembling a number of pawl knobs to form one mechanism permits the pawl selectors of all the pawl knobs to be actuated at the same time by the same shaft and requires provision of only one locking element and separating device.

Similarly to the known devices, the device according to the invention may be constructed so that the direction of rotation of the driving shaft is reversed upon the pawl wheel being locked by the selector pawl, the separating device being, for example, a simple ratchet-gear coupling (a one-way coupling) similar to the above known devices.

However, mechanical locking of the pawl selector enables a more efficient method of operation, according to which the driving shaft, after moving the pawl selector into the selected position, continues to rotate in the same direction so as to actuate the pawl knob shaft. According to the invention this is achieved by constituting the separating device between driving shaft and locking element by an overload coupling instead of by a conventional ratchet-gear coupling.

In order that the invention may be more clearly understood and readily carried into effect, it will now be described more fully with reference to the accompanying drawing, in which the devices which are shown diagrammatically, by way of example, in Figs. 1 and 2 each comprise an overload coupling.

Fig. 1 shows diagrammatically a device comprising three pawl knobs.

Fig. 2 shows diagrammatically only one pawl knob, but any number of pawl knobs may be assumed to be provided.

Fig. 3 shows diagrammatically, by way of example, one embodiment of an overload coupling which, according to the invention, is adapted to be used between driving shaft and locking element.

3

Corresponding parts are designated in Figs. 1 and 2 by like reference numerals.

The two devices shown each comprise a motor 1 which serves to drive the pawl selector as well as the shaft 5 of the pawl knob. They are differentiated in that in the device shown in Fig. 2 the motor is automatically stopped when upon changing their positions all the pawl knobs occupy their new positions, and in the device shown in Fig. 1 the switch of the motor is operated manually.

Referring more particularly to Fig. 1, motor 1 drives a gear wheel 2, which meshes with two further gear wheels 3 and 4. Actuated through gear wheel 3 is a shaft 5 on which are seated pawl selectors 6, 7 and 8, the movement being transmitted from gear wheel 3 15 to the shaft 5 through a shaft 9, a separating device 10 and a set of bevel gears 11.

Driven through gear wheel 4 is a shaft 12, the movement of which is transmitted with the use of a set of bevel gears 13, 14 and 15 to shafts 16, 17 and 18 respectively.

In line with the pawl knob shafts 16, 17 and 18 are the shafts of control members which are operated with the use of the pawl knobs and all of which are actuated at a time by the motor 1. Said control members are not shown.

A system of locking discs is clamped to the shaft of each pawl knob. Each system comprises the same number of discs, for example eight pieces. The drawing shows a single locking disc (19, 20, 21) for each pawl knob and a single rotatable pawl (22, 23, 24) pawl for each pawl knob, but in actual fact each locking disc is associated with such a pawl.

When a pawl is caused, by the pawl selector 6, 7, 8 to co-operate with the locking disc and the latter is actuated, the edge of the disc passes along the pawl until a notch in the disc has reached the pawl. The pawl, which is urged by a stressed spring (25, 26, 27) snaps into the said notch and prevents further rotation of the disc system and hence of the control shaft.

As a rule, all of the pawl knob shafts will not reach the locking position at the same time. Thus, for example, when they rotate in the direction denoted by an arrow at the locking disc 19, the hooked end of the pawl 22 will snap into the notch 28 in the locking disc 19 when the notches 29 and 30 are still remote from the pawls 23 and 24 respectively.

For this reason provision is made between the driving shaft 12 on the one hand and the pawl knob shafts 16, 17 and 18 on the other hand of overload couplings 31, 50 32 and 33, which enable the shaft 12 to continue its rotation when one or more pawl knob shafts are locked.

For this purpose use may be made of a friction clutch or with advantage of an overload coupling of the kind in which the driven shaft is completely separated in the case of overload and due to resilient means operative between the driven shaft and a locking member which remains under the influence of a driving torque. Such an overload coupling is described, for example, in French specification 903.072.

Thus, on the shaft 16 of the device shown in Fig. 1 being locked by pawl 22 it is separated by the over-load coupling 31. Shaft 12 continues to rotate and this movement is followed by the pawl knob shafts 17 and 18. Not until disc 21 has rotated through a larger angle than disc 19 does its notch register with pawl 24 and is it locked in turn. The shaft 18 is then also separated and it is only shaft 17 which continues to rotate but is locked upon the notch 29 in locking disc 20 reaching pawl 23. Thereupon shaft 17 is also separated and the change in position of the control-members is completed.

The co-operation of the pawls with the pawl selector is illustrated in the figure in that the pawls 22, 23 and 24 are lengthened on the other side of their points of rotation by an arm (34, 35 and 36) which bears on the edge of the pawl selector.

The shafts of the pawl knob and the pawl selector may be in line with one another, and in this case the arm of the pawl may be secured to a rotatable shaft which also supports the pawl and is arranged parallel to the pawl knob shaft, the arms of all the pawls being in one plane at right angles to the shaft and the pawls themselves being located in different planes, the shafts of the pawls forming the edges of an equilateral prism.

On the pawl selectors being rotated by the shaft 5, the edges of the pawl selectors pass along the arms of the pawls. The periphery of a pawl selector is circular for the major part but for a small part it comprises a recess (37, 38, 39). On this recess registering with the arm of a pawl, the end of the arm moves into it under the influence of a spring (25, 26, 27) without the pawl selector becoming locked. The end of the pawl adjacent the locking disc is then urged by the spring against the edge of this disc. The angle through which the recess (37, 38, 39) extends need not have an accurately defined value but must be smaller than

$$\frac{360^\circ}{n}$$

n being the number of pawls.

If the pawl knobs are required to change their positions the shaft 5 must be caused to turn and be locked when the recess (37, 38, 39) of the pawl selector registers with the arm of the pawl concerned. The drawing shows the pawl selectors occupying positions in which the arms 34, 35 and 36 are about to move into the recesses of the pawl selectors.

On the shaft 5 starting to rotate, first the pawl of each pawl knob which hitherto was operative is ejected, so that the arrangement for locking discs start to move, the couplings 31, 32 and 33 transmitting the movement from the shaft 12 to the shafts 16, 17 and 18.

In order to lock the pawl selectors provision is made of a locking element comprising an electro-magnetically operated pawl (selector pawl) 49 and a pawl wheel 41, which is firmly seated on the pawl selector shaft 5. This locking element is controlled by a position selector 42. The latter comprises a movable contact arm 43 and as many stationary contact members as there are locking positions of the pawl selector. In the embodiment shown by way of example this number is 8. The stationary contact members are designated I to VIII. They are electrically connected to the corresponding stationary contact members I' to VIII' of a position switch 44, the movable contact member of which is secured to the pawl selector shaft 5. The electric connections may have any length, so that the position selector 42 may be remote from the position switch 44 and the pawl knob mechanism.

Fig. 1 shows the movable contact member of the position switch and its contact arm 45 which cannot contact periodically with more than one stationary contact member of this switch. In this figure the contact arm of the position selector 42 is moved into position I. On the current of the motor I being started with the use of a manual switch 46, the shafts 12 and 5 are set rotating and thus the contact arm 45. As soon as this contact arm contacts the stationary contact member I, as shown in Fig. 1 to have been the case immediately before, a circuit is closed. The current passes in this circuit from one of the terminals 47 of a current source (not shown) through the contact arm 43 of the position selector 42, the stationary contact member I and then through the stationary contact member I' of the position switch 44 and contact arm 45 and thence to the coil 48 of an electromagnet 49. From the coil 48 the current passes directly to the other terminal 50 of the current source. The electromagnet 49 energized by this current attracts its armature 51. This armature is secured to the selector pawl 40 which is thus also actuated by the magnet 49 and moved into its active position.

The pawl wheel 41 comprises as many teeth as there are locking discs on each pawl knob, that is to say eight in the example described. The selector pawl 40 is shown in Fig. 1 to have just dropped on the back of one of the teeth 52 and engages it. On the pawl wheel 41 has turned through a small angle *a*, the front of the next following tooth 53 abuts against the selector pawl 40 and the pawl wheel, and hence also the shaft 5 with the pawl selectors 6, 7 and 8 are locked. At the moment when, this occurs, contact arm 45 is midway on the stationary contact member I', so that an adequate contact is maintained and the doubled over ends of the arms 34, 35 and 36 engage the recesses 37, 38 and 39 of the pawl selectors 6, 7 and 8.

The device might be constructed so that at this instant the direction of rotation of the motor is reversed and not 85 until then the pawl knob shafts are thus set rotating, the

separating device 10 being thus enabled to be a conventional ratchet-gear coupling and a coupling of this kind being also required between the gear wheel 4 and the shaft 12.

In the device according to the drawing, the driving arrangement rotates in the same direction for operating the pawl selectors as for actuating the pawl knob shafts. For this reason the separating device 10 is formed as an overload coupling. This may be a friction clutch but, alternatively, use may be made of a coupling of the kind mentioned above as suitable for use with the shafts 16, 17 and 18.

Consequently, even though shaft 5 is locked by selector pawl 40, the motor and the gear wheels 2, 3 and 4 continue to rotate. The locking discs, which have already started to move a short time after the selectors have come into operation, continue this movement until they are locked in succession by the operative pawls 22, 23 and 24. Upon locking of all the pawl knobs the motor 1 may be held with the use of switch 46, which may be arranged in the proximity of the position selector 42. For subsequently changing the position of the control shafts, all that needs to be done is to displace the contact arm 43 and to close the switch 46. The control current of the magnet 49 is then interrupted and a spring 54 moves the selector pawl 40 into its inoperative position.

In the device shown in Fig. 1 the control current of electromagnet 49 is invariably closed as long as the shafts are stationary. If this is looked upon as inconvenient the locking element may be made to operate otherwise, as shown in Fig. 2, the selector pawl being moved into the inoperative position by the energized electromagnet 49 and into the operative position by the spring 54 and the movable contact member of the position switch being formed into the shape of a disc or a segment 55 and contacting at the same time with all the stationary contact members but one. The disc comprises a recess 56, which is shown in Fig. 2 immediately after having released the stationary contact member I and since the contact arm 43 of the position selector 42 has been moved to engage the stationary contact member I the coil 48 of electromagnet 49 has no longer any current passing through it when this condition prevails. In contradistinction to the device shown in Fig. 1, the control current only flows when the positions of the movable contact members of the position selector and the position switch do not correspond with one another.

In addition, the device shown in Fig. 2 has a motor 1 which is controlled automatically, so that switch 46 of Fig. 1 is omitted from Fig. 2 and the electromagnet 49 operates not only as an actuating magnet for the selector pawl but also as a relay. It operates a switch 57 by means of a make contact connected in series with the motor. Upon the contact arm 43 being moved into a further position not only is the selector pawl 40 of the pawl wheel 41 ejected but also the motor is switched on. Immediately the pawl selectors occupy the selected positions, energization of the magnet 49 ceases, selector pawl 40 reoccupies its active position and switch 57 is opened but the motor is not held thereby, since switch 57 is connected in parallel with a switch 58 which cooperates with the overload coupling 31. Switch 58 is closed so long as the shafts 12 and 16 rotate and is opened when shaft 16 is locked while shaft 12 still rotates. If even more pawl knobs than those shown in Fig. 2 are linked up with the shafts 5 and 12, each of them may be provided with a switch 58. In this case the motor continues to rotate so long as one of the pawl knobs is still moving and its movement does not stop until the last pawl knob shaft is locked and its switch is thus also opened.

An overload coupling operative to control a switch is the subject matter of patent application Serial No. 51,604 now Patent No. 2,659,469, issued Nov. 17, 1953, to Unk. One embodiment of such a coupling will be described, by way of example, with reference to Fig. 3. This figure shows the coupling projected in the axial direction.

The driving shaft which in Figure 3 extends to the front has seated on it a pawl wheel 59. A disk 60, which is adapted to rotate freely about the driven shaft, supports a pawl 61, which engages behind one of the teeth of the pawl wheel 59, so that the disk 60 is carried along with the pawl 61 when the pawl wheel rotates in the direction indicated by the arrow in Fig. 3.

The disc 60 is united with a second disc 62 by two retracting springs 63, of which only one is shown. The

disc 62 is firmly seated on the driven shaft, thus for example, on the pawl knob shaft 16. The springs must be sufficiently rigid to transmit, without excessive extension, the normal torque from the disc 60 to the disc 62. As the torque increases the springs are extended to a further extent, so that the driven shaft slightly lags behind the driving shaft.

Secured to the disc 62 is a stud 64 which extends to the front through a slot 65 of disc 60 and which is moved in this slot upon relative movement of the driven shaft with respect to the disc 60. For a given extension of the springs 63, the stud 64, due to its displacement, engages the pawl 61, urges it upwards and forces it to release the tooth of the pawl wheel 41 by which it is engaged, the shafts being thus fully separated. This occurs, for example, when in the pawl knobs the shafts 16 and so forth are locked, while at the same time the shaft 12 is still rotating under the influence of the motor 1.

Upon the shafts being separated the disc 60 is retracted by the springs 63 and, without further expedites, pawl 61 would be released by the stud 64 and the pawl, which is under spring stress, would re-engage the teeth of the pawl wheel 59. This, however, is prevented by the provision of a clamping device which prevents retraction of the disc 60. It comprises a clamping pawl 66 formed as a roller or a ball which is arranged in a wedge-shaped space between the outer surface of disc 60 and the inner wall of a ring 67 which surrounds the disc 60. When the springs 63 tend to turn the separated disc 60 in the direction opposite to the arrow, the pawl 66 is immediately jammed. This prevents the disc 60 from turning back relatively to ring 67 and the pawl 61 remains

During this time the locked shaft remains subjected to the maximum couple of driving forces that can be transmitted. It is supplied by the springs 63 and the reactive force is the clamping force of the clamping pawl 65 exerted on the ring 67, which constitutes the locking member. Consequently, the pawl knob shafts are not only locked but also fixed in the locking position, so that once a position is adjusted it remains accurately maintained so long as the pawl 22 locks the disc 19. It is due to this couple of forces, supplied by the springs 63, that the shaft 16 resumes movement and thus is re-coupled with the driving shaft upon ejection of the operative pawl 22.

The ring 67 is not secured firmly to the fixed plate 68 but is adapted to turn through a small angle relatively to this plate. The stressed springs 63, together with the disc 60 and the clamping pawl 66 are thus enabled to turn the ring 67 slightly in the direction opposite to the direction of rotation of the shaft. The movement of ring 67 and the play in the clamping coupling must, however, not result in the stud 64 being pulled from the pawl 61. There must, therefore, be some back lash in the co-operation between the stud 64 and the pawl 61. Since this does not fall within the scope of the invention, and is known in the prior art, it will not be given further consideration.

The stroke of the ring 67 is limited by a lug 69 engaging a slot 70 in the plate 68. This lug has secured to it a link member 71, which co-operates with the switch 58. The movement performed by the ring 67 under the stress of the springs 63 upon disengagement of the shafts results in this switch being opened.

It is desirable that the rotary speed of the pawl selector should exceed that of the pawl knob shaft, so that unless the difference between two locking positions of the pawl knobs is excessively small, the selector has taken up its new position before the pawl knob has reached its position. However, two selected successive positions of the pawl knob may be in such close proximity to one another that a slight release of the springs, which does not yet cause the pawl 61 to engage the pawl wheel 59 is sufficient for the pawl knob to move from one position into the other. In this case the switch 58 is not closed and hence, on the switch 57 being opened by the spring 54, the motor 1 is not kept actuated by a current passing through the switch 58. The movement of the motor 1 and hence also of the pawl wheel 41 is then stopped at an instant when the tooth 53 has not yet contacted selector pawl 40. This might give rise to disturbances, such as inadequate penetration of the pawls.

Accordingly, according to the invention, the overload

coupling 10 is provided, between driving shaft and selector shaft, with a switch 72 operating in a manner similar to that of the switch 58 and similarly thereto connected in parallel to switch 57. Switch 72 is closed so long as both the shafts 9 and 73 coupled by coupling 10 rotate. Consequently, in the event of switch 58 not taking the function of switch 57 when the latter is opened, this is done by switch 72. Hence, even in this case the motor continues to rotate until the pawl selector shaft is locked, whereupon the shafts 9 and 73 are separated with the result that switch 72 is opened.

Even though switch 72 is present, switch 57 cannot be dispensed with, since the former is capable of breaking the circuit but not of starting the motor. When the pawl selector shaft 5 is unlocked while the shaft 9 is still stationary, the springs 63 of the overload coupling release and pull the shaft 73 along with them, but the locking member 67 is not subjected to any force that urges it into the direction of rotation of the shaft until the driving shaft together with the pawl wheel 59 starts to rotate. The switch 57 is therefore required to close the circuit of the motor.

What we claim is:

1. A shaft positioning device including a pawl knob, said pawl knob comprising a pawl selector, a locking disc, and a pawl member mounted in operative relationship with said pawl selector and said locking disc, said pawl selector comprising means for rendering said pawl operative to engage said locking disc in locking relationship therewith in a predetermined position of said pawl selector, undirectional and common driving means for said pawl selector and said locking disc, an overload coupling interposed between said common driving means and said pawl selector, said overload coupling comprising means for completely separating said pawl selector from said driving means upon overload and resilient means operable upon such separation to subject said pawl selector to a driving torque, and selectively operable means for locking said pawl selector in said predetermined position.

2. A shaft positioning device including a pawl knob, said pawl knob comprising a pawl selector mounted on a first shaft, a locking disc mounted on a second shaft, a pawl member mounted in operative relationship with said pawl selector and said locking disc, said pawl selector comprising means for rendering said pawl operative to engage said locking disc in locking relationship therewith in a predetermined position of said pawl selector, common electric motor driving means for said pawl selector and said locking disc, a circuit connected to said electric motor means for energizing the same, a switch in said circuit, a separating device interposed between said common driving means and said pawl selector for completely separating the connection between said driving means and pawl selector upon overload, selectively operable means for mechanically locking said pawl selector in said predetermined position, and electromagnetic control means controlling both said switch and said selectively operable means for locking said pawl selector.

means for locking said pawl selector.

3. A shaft positioning device including a pawl knob, said pawl knob comprising a pawl selector, a locking disc, and a pawl member mounted in operative relationship with said pawl selector and said locking disc, said pawl selector comprising means for rendering said pawl operative to engage said locking disc in locking relationship therewith in a predetermined position of said pawl selector, common electric motor driving means for said pawl

selector and said locking disc, a circuit connected to said electric motor means for energizing the same, a first switch in said circuit, an overload coupling interposed between said common driving means and said pawl selector, a second overload coupling interposed between said common driving means and said locking disc, selectively operable means for locking said pawl selector in said predetermined position, and control means for said switch, said control means being actuatable by said means for locking said pawl selector, a second switch connected in parallel with said first switch, and means actuated by said second overload coupling for controlling said second switch.

switch.

4. A shaft positioning device including a pawl knob, 15 said pawl knob comprising a pawl selector, a locking disc, and a pawl member mounted in operative relationship with said pawl selector and said locking disc, said pawl selector comprising means for rendering said pawl operative to engage said locking disc in locking relationship therewith in a predetermined position of said pawl selector, common electric motor driving means for said pawl selector and said locking disc, a circuit connected to said electric motor means for energizing the same, a first switch in said circuit, a first overload coupling interposed between said common driving means and said pawl selector, a second overload coupling interposed between said common driving means and said locking disc, selectively operable means for locking said pawl selector in said predetermined position, and control means for said switch, 30 said control means being actuatable by said means for locking said pawl selector, a second switch connected in parallel with said first switch, and means actuated by said second overload coupling for controlling said second switch, and a third switch connected in parallel with said first and second switches, and means actuated by said first overload coupling for controlling said third switch.

40 first overload coupling for controlling said pawl members.

45 5. A shaft positioning device including a pawl knob, said pawl knob comprising a plurality of pawl selectors and a plurality of corresponding locking discs, a plurality of pawl members each mounted in operative relationship with each pawl selector and corresponding locking disc, each pawl selector comprising means for rendering an associated pawl member operative to engage an associated locking disc in locking relationship therewith in a predetermined position of said pawl selector, unidirectional and common driving means for said pawl selectors and said locking discs, an overload coupling interposed between said common driving means and said pawl selectors, and selectively operable means for locking said pawl members in a number of predetermined positions equal to the number of pawl members, said selectively operable means comprising a pawl and a pawl wheel, and a position selector controlling said selectively operable means.
